United States Patent Office

Des. 228,320

Patented Sept. 11, 1973

228,320

SNACK FOOD PRODUCT OR THE LIKE

John D. Forbes, Battle Creek, and Joseph John Thompson, East Jordan, Mich., assignors to Kellogg Company, Battle Creek, Mich.

Filed Sept. 5, 1972, Ser. No. 286,270

Term of patent 14 years

Int. Cl. D1—01

U.S. Cl. D1—1

FIG. 1 is a plan view of a snack food product or the like showing our new design, the view depicting the top or the bottom thereof as both are the same;

FIG. 2 is an end view thereof;

FIG. 3 is a side view thereof; and

FIG. 4 is a cross-section thereof taken on line 4—4 of FIG. 1.

We claim:

The ornamental design for a snack food product or the like, substantially as shown and described.
